UNITED STATES PATENT OFFICE.

ROY E. COMBS, OF DES MOINES, IOWA.

SMOKING-PIPE.

1,168,481.

Specification of Letters Patent.

Patented Jan. 18, 1916.

Application filed September 1, 1914. Serial No. 859,654.

To all whom it may concern:

Be it known that I, Roy E. Combs, a citizen of the United States, residing at Des Moines, in the county of Polk and State of Iowa, have invented a new and useful Improvement in Smoking-Pipes, of which the following is a specification.

My invention relates to smoking pipes.

The objection of my invention is to produce a pipe having a stem and bit in separate parts, and provided with connecting means between said bit and stem in which the strain of supporting the bowl is so distributed over the several parts of the structure as to substantially approximate the strength of an integral stem.

A further object of my invention is to produce a pipe stem comprising a stem proper, a bit and a connecting screw or plug in which the screw or plug projects into both of said members, and in which the stem telescopes the bit and the bit telescopes the plug longitudinally whereby the adjacent vertical edges of the stem and bit contact at a point offset from the contacting longitudinal faces thereof, and whereby the supporting strain is distributed over the entire three parts of the structure and the abutting faces of the stem and bit.

30 A still further object of my invention is to produce a more durable and efficient separable stem and bit for pipes than has heretofore been attained.

To these ends, my invention includes the combination and arrangement of component parts to be hereinafter described and more particularly pointed out in the claim.

In the accompanying drawings in which like reference characters indicate similar parts, Figure 1 is a longitudinal sectional view of my invention, and Fig. 2 is a detail view of the parts thereof.

Referring to the drawings, 1 indicates the bowl of a pipe having a stem 2 integral therewith which is provided with a longitudinal duct connecting with the bowl. The outer end of the stem is bored to form a projecting ring or annular flange 3 designed to telescope and embrace the inner end of the bit 6 as hereinafter described. Adjacent said enlarged bore and ring 3, the duct of the stem is enlarged and the wall thereof is interiorly threaded at 4 to receive the threaded end of the plug 5 as also later described herein.

The screw or plug 5, as shown, comprises the stem portion A and the bit portion B, the former or stem portion being provided with screw threads on its surface to cooperate with the interior threads in the bore 60 of the stem. The bit portion B projects beyond the end of the stem and fits into the central socket C in the adjacent end of the bit 6. The portion of said bit adjacent to the stem is provided with a projecting 65 annular flange 7 which extends into the ring or flange 3 on the stem 2 and forms an annular shoulder D on the bit against which the end of the flange 3 abuts when the parts are assembled.

In the ordinary pipe it is well known that the breaking of the stem or bit is frequent, and that the break occurs almost always at the point where the stem and bit are joined together and where their vertical faces meet. 70 A stem and bit connection embodying the features of my invention as hereinbefore described, will do away with the weakness of the ordinary pipes for the reason that the screw or plug 5 extends beyond the telescoping parts of the pipe stem and bit in both directions, so that the screw or plug 5 furnishes a reinforcing member extending beyond all the joints between the stem and bit. 75 In this connection it may be mentioned that such construction so reinforces the joint that the stem and bit will not break at the joint, and will break somewhere else first even though the material used for the plug is bone or the like, and if the plug is made of 80 metal the pipe is practically unbreakable at the joint between the stem and the bit. If the plug should be made to extend only to the position flush with the shoulder D, or flush with the end of the flange 3 next 85 to the bowl, the purpose of my invention would not be accomplished, for with such a construction as is just mentioned a break would occur in line with one of the parts mentioned. It is important that the screw 90 or plug 5 should extend beyond all the joints between the stem and the bit in order to properly reinforce such stem and bit and to prevent any breaking at the joints.

It will be appreciated that the parts and 95 combinations thereof may be varied within a wide range within the scope of the claims without departing from the spirit and scope of the invention.

Having thus described my invention, what 100

I claim as new and desire to be secured by Letters Patent, is—

A separable stem for smoking pipes, comprising a bowl stem having a screw-threaded interior socket, a projecting annular flange thereon adapted to telescope and embrace the adjacent end of a bit, a bit having a projecting annular flange extending within the annular flange on the adjacent bowl 10 stem and having a smooth-faced interior socket extending beyond the flange, and an interior longitudinal plug having screw

threads at one end to engage the interior threads on the bowl stem and a smooth surface on the opposite end extending into the 15 socket in the bit beyond the flange on the bit, whereby a separable joint is formed and the strain of supporting the bowl is sustained and distributed over all the parts, substantially as described.

ROY E. COMBS.
